ACCESSORY FOR BICYCLE REARING ACTIONS

Harold Hasselbusch, 144-21 68th Drive,
Flushing, N.Y. 11367

Filed Oct. 17, 1969, Ser. No. 19,610

Term of patent 14 years

Int. Cl. D12-14

U.S. Cl. D90-1

FIG. 1 is an elevational view of one side of an accessory for bicycle rearing actions, showing my new design, the opposite side being the same;

FIG. 2 is a top plan view;

FIG. 3 is a bottom plan view;

FIG. 4 is a rear end elevational view; and

FIG. 5 is a front end elevational view.

I claim:

The ornamental design for an accessory for bicycle rearing actions, as shown.
